Primary Examiner — Jennifer L Watkins*Assistant Examiner* — Samantha Lynne Brodowski(74) *Attorney, Agent, or Firm* — Knobbe, Martens, Olson & Bear, LLP(57) **CLAIM**

The ornamental design for a bag as shown and described.

DESCRIPTION

1. Bag

1.1: Perspective

1.2: Front

1.3: Top

1.4: Bottom

1.5: Left

The design consists of a cylindrical shaped bag including a bag strap, zipper and dashed lines being stitching, all of which form part of the scope of protection of the design. The bag strap is shown in a first position in Reproductions 1.1, 1.2, and 1.5, and in a second position in Reproduction 1.3 and 1.4. The bag is to be used for carrying items and to be worn as a fashion accessory.
